BELT PACK

Alan H. Zerobnick, P.O. Box 6638, Cherry Creek Station,
Denver, Colo. 80206, and David J. Cole, Denver,
Colo.; said Cole assignor to said Zerobnick

Filed June 3, 1974, Ser. No. 475,422

Term of patent 14 years

Int. Cl. D2—07

U.S. Cl. D2—381

FIG. 3

FIG. 1 is a side perspective view of a belt pack showing our new design in wearing position;

FIG. 2 is an end elevational view of the belt pack as seen from the right end of FIG. 4 but with the strap end in a flat extended position;

FIG. 3 is an elevational view of the opposite end;

FIG. 4 is a front elevational view of the belt pack in an extended unfastened position with the end of the strap doubled over for convenience of illustration;

FIG. 5 is a bottom plan view thereof;

FIG. 6 is a back elevational view taken from the side opposite to the front view of FIG. 4; and

FIG. 7 is a top plan view.

We claim:

The ornamental design for a belt pack, as shown and described.
